DESIGN FOR A MITTEN

Benjamin Ginsberg, New York, N. Y.

Application July 23, 1941, Serial No. 102,391

Term of patent 7 years

To all whom it may concern:

Be it known that I, Benjamin Ginsberg, a citizen of the United States and resident of New York city, in the county of New York and State of New York, have invented a new, original, and ornamental Design for a Mitten, of which the following is a specification, reference being had to the accompanying drawing, forming a part hereof.

In the drawing:

Fig. 1 is a rear view of a mitten showing my new design, and

Fig. 2 is a front view of the mitten shown in Fig. 1.

I claim:

The ornamental design for a mitten, as shown.

BENJAMIN GINSBERG.
